[54] COMBINATION ADULT AND CHILD
TOILET SEAT AND COVER

3,205,510 9/1965 Levine 4/234
3,517,396 6/1970 Wert 4/234

[76] Inventor: James R. Sessions, 127 Thayer Way,
Vallejo, Calif. 94589

Primary Examiner—James R. Largen
Assistant Examiner—Cathy Anne MacCormac
Attorney, Agent, or Firm—Linval B. Castle

[] Term: 14 Years

[57] CLAIM

[21] Appl. No.: 876,355

The ornamental design for a combination adult and child toilet seat and cover, as shown and described.

[22] Filed: Jun. 19, 1986

DESCRIPTION

[52] U.S. Cl. D23/296; D23/295;
D23/311

[58] Field of Search D23/296, 311; 4/234;
5/90, 463

FIG. 1 is a top plan view of a combination adult and child toilet seat and cover showing my new design;
FIG. 2 is a side elevational view thereof; the opposite side being a mirror image of the side shown;
FIG. 3 is a front elevational view thereof;
FIG. 4 is a bottom plan view thereof;
FIG. 5 is a rear elevational view thereof;
FIG. 6 is a sectional view taken along line 6—6 of FIG.
1; and
FIG. 7 is a perspective view thereof in open position.
